UNITED STATES PATENT OFFICE.

MALONE WHELESS, OF WASHINGTON, DISTRICT OF COLUMBIA.

ELECTRIC-ARC LAMP.

SPECIFICATION forming part of Letters Patent No. 548,683, dated October 29, 1895.

Application filed June 8, 1895. Serial No. 552,159. (No model.)

To all whom it may concern:

Be it known that I, MALONE WHELESS, a citizen of the United States, residing at Washington, in the District of Columbia, have invented certain new and useful Improvements in Electric Lamps; and I do hereby declare the following to be a full, clear, and exact description of the invention, such as will enable others skilled in the art to which it applies to make and use the same.

This invention relates to an improvement in electric-arc lamps, more especially to such a lamp as is shown in my applications for United States patents filed April 27, 1895, Serial Nos. 547,393 and 547,394. The present construction illustrates the principles which are contained in such applications; but the present case shows the lamp in substantially the completed form, in which it will be made and put into use.

The invention consists in the details of construction hereinafter pointed out and claimed.

In the annexed drawings, Figure 1 represents an elevation of the entire device. Fig. 2 represents a detailed view of the counterweight. Fig. 3 represents a vertical diametric section through one of the main solenoids. Fig. 4 represents a partial transverse diametric view and a horizontal diametric view of the core of the solenoid. Fig. 5 represents a top view of the negative-carbon holder. Fig. 6 represents several views of the cut-out. Fig. 7 represents an enlarged transverse view of the same. Fig. 8 represents a diagrammatic view of the wiring.

In the drawings, the letter A represents the light-chamber, which is secured in the usual way to the cap B, provided with the top central hollow boss b. Passing down through and secured firmly within this boss b is the positive-carbon holder C, containing the positive carbon D. Within the light-chamber A this positive-carbon holder C is made near its lower end c with opposite slots c'. Secured to the carbon-holder C at these slots c' is a band E. In the ears e of this band E are pivoted the grip-cams F, whose operative edges pass through the slots c' and rest against the positive carbon D. The outer ends of these cams F are pivoted to hangers f', whose upper ends f² are pivoted in a yoke G. This

yoke G is secured to a sleeve g, which loosely surrounds the positive-carbon holder C. This yoke G is secured by nuts above and below it, at its ends, to rods h. The counterweight G' is pivoted by its arms g' to each side of the yoke G, such counterweight being also pivoted by the lugs g² to the brackets g³, depending from the cap B. This counterweight and the brackets are shown in dotted lines in Fig. 1, so as not to confuse the drawings.

The rods h pass through the cap B, through tubes h', and are secured to the cores H of the main solenoids I. These cores H are made of a number of vertical rods h², held together by caps h³, as clearly shown in Fig. 4. Secured to the supports of the main solenoids is a plate L, on top of which is placed a small solenoid l. To the under side of the plate L is secured a bracket l', in which is pivoted the lever M, which forms one part of the cut-out. At the end of this lever M is made a head m', consisting of the several layers m² m³ m⁴ m⁵, consisting, in order, of red fiber, metal, red fiber, and metal, secured together by the bolts m⁶. Secured to the under side of the metal plate m⁵ is the carbon contact m⁷. Supporting-rod n depend from the plate L and carry the other portion N of the cut-out. This consists of the fiber plate n' and metal plate n², held together by bolts n³, and this part N carries the other carbon contact n⁴.

Insulated to the cap B is the binding-post O to the negative-carbon holder. This consists of rods o and o', held together by the tube o², and the negative-carbon clamp P. This clamp P has two jaws p and p'. The jaw p' is held by the sleeve p² upon a horizontal rod p³, which is held in the lower end of the rod o'. Rising from the other end p⁴ of this rod p³ is the bar p⁵, in which is a set-screw p⁶ and a steady-pin p⁷. The inner ends of the set-screw p⁶ and the steady-pin p⁷ engage the rear face of the jaw p. Between the two jaws p and p' the negative carbon Q is held, and it is clamped between the two jaws by operating the set-screw p⁶, the steady-pin p⁷ preventing the jaw p from turning.

On the top of the cap B is placed the positive binding-screw b', and in the cap B is made the usual safety-valve R.

The solenoids I are made of coarse and

fine wire, as clearly indicated in Fig. 3, the wires being wound in reverse directions.

The line-wire is connected with one solenoid I and to the lever M of the cut-out. The 5 positive wire passes from the first solenoid I to the second solenoid I, thence to the small solenoid l, and thence to the positive binding-screw b'. From the part N of the cut-out the negative wire passes to the binding-screw O, 10 and from this binding-screw the negative wire passes off to the line.

When the current is turned on, the three solenoids I, I, and l are vitalized. The two solenoids I operate in the usual way by the 15 difference in the electromotive force produced by the differentiation between the reverse currents passing through the coarse and fine windings. The cores H are acted upon by the solenoids and through the yoke G and 20 cams F act upon the positive carbon D. While the lamp is in use, the solenoid l is active and keeps open the cut-out M N. Should the lamp from any cause become inactive, the

solenoid l becomes devitalized, the two parts M N contact, and the current passes around 25 the lamp.

Having described my invention, what I claim is—

1. The combination of the yoke, G; the cap, B, and the counter-weight, G'; the counter- 30 weight being pivoted both to the cap and the yoke, as set forth.

2. The combination of the jaws, p, p'; the latter having the sleeve p², the rod, p³; the bar, p⁵; the set screw, p⁶, and the steady pin, 35 p⁷, as set forth.

3. The lever, M, having the head, m', consisting of the several layers, m², m³, m⁴ and m⁵, consisting in order of red fiber, metal, red fiber and metal, and the bolts, m⁶, as set forth. 40

In testimony whereof I affix my signature in presence of two witnesses.

MALONE WHELESS.
